BOWLING ALLEY BED

George C. Debay, Los Angeles, Calif.

Application June 12, 1937, Serial No. 147,981

1 Claim. (Cl. 273—51)

This invention relates to a bowling alley of standard size but of a construction that makes it suitable for outdoor as well as for indoor use. The construction is such as will permit the entire bowling alley to be taken apart and reassembled. The alley is made up of sectional parts, each part having means to rigidly hold it to its neighboring part in a manner to assure an even and flush rolling surface equivalent to a monolithic-like structure, or a structure made of integral parts.

Means are provided in association with the metallic parts of the bowling alley to absorb the metallic sound and thus make such an alley practically as noiseless as the ordinary alley built of wood. In fact, such absorbent means is so situated and arranged so as to act as a cushion for the metallic alley and in this way provide sufficient resiliency to absorb shocks and greatly reduce the amplitude of the sound waves which would ordinarily be set up by metallic plates.

Most any kind of metal may be employed in the construction of the bowling alley whether the surface is treated or not to hinder the action of the atmospheric elements. The inventor, however, prefers to use Monel metal or stainless steel for the reason that these metals can be easily washed and kept clean. Such metals and their derivatives, when washed in the simplest manner, can be thoroughly cleaned and their bright lustre retained indefinitely.

The prime object of the invention is the provision of a structure which will be practically noiseless and sound-proof as well as impervious to and unaffected by the elements such as moisture, wind, heat, dust, dirt, etc.

Another object is to provide a structure of the foregoing type so constructed and arranged as to be composed of a plurality of sections or units, each provided with interlocking means at its ends so that the units can be rigidly secured together to form a unitary whole while at the same time being capable of being easily and quickly disconnected or dismantled when necessary or desirable for transportation or storage.

A further object is to provide, in a structure of the above type, means at, or near, the abutting ends of the units for maintaining these units in perfect surface alignment so that when assembled for use a smooth unbroken playing surface will be provided.

A still further object is to provide a construction of the above type which will be simple in construction, light in weight, of a maximum dura-

bility and efficiency and of a very attractive appearance.

Other objects and advantages will appear hereinafter and, while I have shown and will describe the preferred form of my invention, it will be understood that I do not limit myself to such preferred form but that various changes and adaptations may be made therein without departing from the spirit of my invention. No limitations whatever are to be placed upon my invention except those expressed in the dependent claim.

In the drawings accompanying and forming a part hereof:

Figure 1 is a perspective view of a double bowling alley constructed according to my invention.

Figure 2 is a section on the line 2—2 of Figure 1.

Figure 3 is a section on the line 3—3 of Figure 1.

Figure 4 is a top plan of one of the sections of playing field or runway.

Figure 5 is a right hand end elevation of Figure 4.

Figure 6 is a transverse section of Figure 4.

Figure 7 is a section on the line 7—7 of Figure 4.

Figure 8 is a side elevation of Figure 4.

Figure 9 is an enlarged fragmentary perspective of a portion of my structure.

Figure 10 is a schematic transverse diagram of Figure 1.

Figure 11 is an enlarged fragmentary view (top plan) showing the connection between the abutting ends of two of the units forming my structure.

Figure 12 is a section taken substantially along the line 12—12 of Figure 11.

Figure 13 is a left hand elevation of Figure 11.

Figure 14 is a section on the line 14—14 of Figure 11.

Figure 15 is a diagrammatic view showing the method of assembling the elements of my device.

Figure 16 shows a perspective view of a modified form of the invention with the floor plate removed.

Figure 17 shows a longitudinal cross section.

Figure 18 is a view substantially on the line 18—18 of Figure 17, parts being in section.

Now, by reference to the drawings, one form of the invention is set forth in sufficient detail to enable one skilled in the art to make, construct and use the same.

Numeral 1 represents a twin set of bowling alleys; this particular illustrated structure having the usual alley back-stop sub-structure com-

prising end walls 2 and 3 fixed to dividing partitions 4, 5 and 6. The partition 5 separates two adjoining spill and scatter compartments 7 and 8 and generally has supports or has juxtaposed thereto the raised portion 9 of a ball return track 10. This track, at the other end of the alley, has another raised portion 11 of sufficient length to accommodate any number of balls desired for use in both alleys. A ball stop 12 is employed at this end and may be faced with any suitable material to absorb the shock of balls which may strike it. Inclines 13 and 14 are provided connecting the track 10 with raised portions 9 and 11, the raised portion 9 being of higher elevation than portion 11 to assure full return of the balls.

The spill and scatter compartments 7 and 8 have pits or sunken portions 15 and 16 which have floors 17 and 18 of earth or of a construction like the runway or alley floor units to be presently described. The pit wall 19 is provided which may be of any material suitable for the purpose.

The numeral 20 indicates the playing field, runway, slideway or rolling surface of the bowling alley, one end of which, indicated by 21, is a space for setting up wooden or metallic pins to be struck down by wooden or metallic balls as in the game of ninepins or tenpins. It is here understood, however, that the runway or slideway 20 is a surface over which any object, missile or the like may be rolled, slid or projected and further, the objects to be struck may be of any kind or nature. The inventor is well aware of the fact that the elements and apparatus herein described may not necessarily be limited to the game of tenpins.

Lengthwise upon either or both sides of the runway or slideway 20 are gutters 22 and 23 for arresting the ball or balls and leading them to the pit 16. Low partitions or barriers 23a prevent the balls from leaving lateral edges of the alley when rolled hard toward the gutters.

The playing field or runway 20 is composed of a plurality of sections or units 24, as shown in section in Figures 7 and 12, each comprising a rectangular plate 25, preferably of metal, although any other desired or suitable material may be used, the upper face of which forms the playing field or runway. Rigidly secured along the longitudinal edges of plate 25, on the underside thereof, are angle irons or inverted L-shaped supporting members 26 and 27, the downwardly depending legs of which are flush with the longitudinal edges of plate 25 and the horizontal legs of which extend inwardly towards each other. These members 26 and 27 project for a short distance beyond one traverse end of plate 25 and are inset a similar distance from the other traverse end of said plate. Rigidly secured along the traverse edges of plate 25 on the underside thereof and between the ends of members 26 and 27 are traverse connecting members 28 and 29, these members 28 and 29 forming with members 26 and 27 a substantially rectangular frame upon which plate 25 is mounted, this frame being of the same size and shape as plate 25, and may be, if desired, welded or otherwise rigidly fabricated together. Extending lengthwise of plate 25, centrally thereof, is a T-shaped supporting beam or member 30, the ends of which may be welded or otherwise connected to the cross members 28 and 29. It will be noted that by this construction two parallel, longitudinally extending, downwardly opening recesses or pockets 31 and 32 are formed or provided on the underside of plate 25, and in these pockets or recesses are positioned the sound absorbing or

deadening means 33 and 34 of rock wool, glass wool, steel wool, fabricated cotton or pulp boards or any other suitable or desired material. Secured at suitable intervals to the downwardly depending legs of the supporting members 26, 27 and 30 are brackets 35 and 35a and screwthreadedly mounted in these brackets are screws 36. Extending transversely beneath the sound absorbing or deadening means 33 and 34 and reaching between opposed brackets 35 and 35a are supporting plates 37 and 37a, the ends of which rest upon the upper ends of the screws 36 and provide means for supporting the sound absorbing means in firm contact with the plate 25. Any number of these supporting plates may be employed, the number to some extent depending upon the sound absorbing material used. Rigidly secured to the members 26 and 27, at one end thereof are blocks 40, see Figure 11, through which are provided over-bored angularly extending holes 41. These blocks may be of any suitable material, but metal is preferred. Rigidly secured to the opposite ends of said members 26 and 27 are similar blocks 42 through which are provided angularly disposed, screw threaded holes 43, these blocks and holes being so arranged that when the units are assembled for use the holes 41 and 43 are in longitudinal alignment and a screw 44, passing therethrough, provides means for drawing the abutting ends of the units together and holding the same in correct alignment, the holes 41 being of a size sufficient to permit the screw 44 to move sidewise therein. A beveled washer 45 is provided between the head of the screw 44 and block 40 to compensate for the angular difference between the face of said block 40 and the bearing face of the head of the screw 44. Slots 40a are provided in the downward legs of the angle irons 26 and 27 for the entrance of a wrench to engage the head of the screw 44.

The gutter members 46, see Figure 9, are preferably formed of sheet metal although any other suitable or desired material may be used, the central portion of which is bent or otherwise formed into a trough 47, the material along one side of which is bent downwardly to provide a downwardly depending integral flange 48 in which are formed, at suitable intervals, downwardly opening slots 49 adapted to be fitted over the headed studs 50, projecting outwardly from the outer faces of the supporting angle iron members 26 and 27, and be supported and held positioned thereby. Along the opposite edge of trough 47 is formed an outwardly extending horizontal flange 51 and along the outer edge of this flange 51 is formed an upstanding rim 52. The partitions 23a are preferably formed of sheet metal or any other suitable or desired material and are bent or otherwise formed into a substantial inverted U-shape in transverse section having a flat top 53, one of the downwardly depending legs 54 resting upon the flange 51, inclosing rim 52 and being normally secured thereto. The other leg 55 is similarly connected to the gutter of the next adjoining alley, if there is one, otherwise a suitable support or connection will be provided.

The ball returns are preferably composed of two companion members identically formed but reversed as to each other when assembled for use. These members are preferably formed of sheet metal or other desired or suitable material and are bent or otherwise bent or formed to provide a narrow central portion 56 along one edge of which is a downwardly depending right angled leg 57 arranged to normally rest upon the flange 51 of the gutter or trough 47, inclosing the upstanding

rim 52 and being normally secured thereto. Along the opposite edge of the portion 56 is an angularly, downwardly depending portion 58, the lower termination of which is bent to form a 5 narrow vertically extending rim 59. At suitable intervals these opposed rims 59 will be connected by transversely extending U-shaped tie members 60 to form a trough or runway, the sides of which extend angularly and downwardly towards each 10 other to provide accommodations for varying sizes of playing balls. These gutters or troughs, together with the runways, will be made in lengths substantially equal to the lengths of the playing field units 24 for ease of transportation or storage 15 and the abutting ends will be connected in any suitable or desired manner to insure correct alignment.

Suitable means, such as screw jacks or the like, may be provided, if found desirable or necessary, 20 to assist in leveling or alining the device, or any other means may be used.

Provided at suitable intervals through the inner wall of the troughs 47 are ventilating openings 46 for the purpose of a circulation of air beneath the 25 units when assembled for use, the purpose of which will be obvious.

Figures 10 and 15 show a traverse sketch of the bowling alley and the approximate position and joints of the various longitudinal parts. For 30 the sake of simplicity, the joints were not shown as touching but, it is obvious, that all the joints and seams must be rigidly held together so that the entire bowling alley and its associate parts are as a single integral unit. As shown in Figure 9, the gutters 47 are held removably fixed to the alley units by bayonet-like slots and headed pins. The adjoining gutters are held together by the interfitting elements which make up the ball return tracks, partitions like 23a interfitting 35 with gutters where ball return tracks are not used. All the joints and seams to be permanently held together are either soldered, welded, bolted or riveted together, preferably welded together. The traverse joints and seams, except 40 the alley floor units, may also be welded, soldered, or riveted where not to be separated but, since all lengths of the various parts are to be removably fixed together for convenience of carrying, and shipping and storing purposes, they are bolted 45 or/and screwed one to the other or bayonet slots and pins are provided so that they can be latched together.

The modified form of the invention shown in Figures 16, 17 and 18 will now be described.

This form relates to the sectional floor structure 55 and means of supporting and leveling same. Each section or unit which makes up the alley or runway has a rectangular floor plate 70 of suitable metal, fixed to a sub-floor 71. The sub- 60 floor may be metal or other suitable material cast or fabricated into a single integral or monolithic piece. The material may be pot metal, bauxite or any derivative thereof. Any cheap porous substance may be used which has the 65 requisite strength and can withstand the climatic conditions wherever it may be employed. This sub-floor is reticulated and formed as a gridiron having pockets or chambers 72 filled with a sound

absorbing substance such as asphalt compounds, various wools, or any plastic substance suitable for the purpose. Relatively thin fin-like partitions 74 separate the chambers and provide strength to support the floor plate and the loads 5 and shocks to be expected. Thick flanges 75 and 76 provide added strength and the means for connecting adjoining sub-floor sections together so that their respective floor plates are in perfect alinement to provide an even flush 10 surface for the runways. The flanges 75 and 76 of adjoining floor sections have tongue and groove fit; the flanges 75 being provided with a tongue 77 and flanges 76 with a groove 78. Bores 79 are provided in the flanges through which 15 pass bolts 80. Nuts 81 are screwed tightly upon the bolt ends when adjacent floor sections are properly assembled to hold them in perfect alinement. Vertical bores 82 in the flanges receive screws 83 which enter threaded holes 83a in the 20 floor plate and tightly draw the plates down upon the sub-floor structure. Shoulders 84 are provided upon the flanges 75 to form a seat for an under plate 85. Bosses 86, bored and threaded, are integral with the partitions 74 and receive 25 screws 87 which pass through holes in the under plate 85; the screws holding the under plate tightly against the casting 71. Casted with the 30 sub-floor elements 71 are studs or legs 88 depending from the lateral borders thereof. Unthreaded over-bored holes 89 are provided in each leg which loosely receive the ends of bolts 90 having running threads and lock nuts 91. The bolt heads 92 rest in an elongated channel 93 which may be anchored to or merely rest upon 35 concrete posts 94. The concrete posts may be set in the ground at predetermined intervals in alinement, to support the channels 93 substantially level. By adjusting the nuts 91, the floor plates can then be accurately leveled and thus 40 present a perfect floor surface for the game of tenpins or for any other purpose.

The channels 93 may be iron, steel, stainless steel or any other material strong enough for carrying the load and shocks of the floor above. 45 These channels run the entire length of the assembled alley or runway, but may be divided into convenient handling lengths with means for joining them together.

I claim:

In a bowling alley construction having playing surface elements with their edges in abutment to form a continuous alley, a plurality of base sections having their edges in abutment and in alignment with said elements to support them, 55 flanges along the abutting edges of said sections and means provided therein to hold adjoining sections together and also means to hold said elements to said sections, a plurality of pockets in each of said sections, sound absorbing material filling each pocket to maintain contact with the under side of their respective elements, an under plate for each section, threaded means for drawing the plates toward said elements to assure contact of the sound absorbing material 60 against the elements. 65

GEORGE C. DEBAY.
